UNITED STATES PATENT OFFICE

2,566,913

CABLE DRILLING TOOL

George R. Watson, Waukegan, Ill.

Application April 15, 1949, Serial No. 87,803

6 Claims. (Cl. 255—27)

1

My invention relates to cable tools and more particularly to a string of cable tools for drilling oil or water wells and for drilling blast holes in mines and quarries.

The conventional string of cable tools commonly used in combination with a steel cable, consist of a cable socket, a pair of link type or cylinder type jars, a solid steel drill stem and a drill bit, all of which are parts joined by means of threaded box and pin joints for the purpose of raising the entire tool by means of the cable, and allowing them to fall freely, thereby providing an impact of the chisels forming an integral part of the drill bit, within the bottom of the hole being drilled.

Obviously the progress of deepening the hole is a direct result from the rotation of the tool during the churn action and its impact, and it is therefore necessary to provide a swivel at the end of the cable connecting the cable to the tool by means of a rope socket. The rotation of the tool is the direct result of the unwinding of the cable due to the heavy tension on the cable when the tool is raised in the "up" stroke and the twist of the cable to its normal position when the tension on the cable is released and the tool is dropped by gravity in its "down" stroke. This twisting of the cable causes the rotation of the tools and is sufficient when a small drill bit is employed, but when larger drill bits are used, the sludge is of heavier consistency and the drill bit has a tendency to stop rotating and to cut a flat hole or to follow a seam in the formation being drilled.

The object of my invention is to provide a string of cable tools that eliminates the weakness and breakage caused by the conventional threaded box and pin joints.

Another object of my invention is to eliminate the breakage of the links or reigns in the drill jar, thereby eliminating the expensive "fishing" operation to retrieve the string of tools when the cable breaks.

Still another object of my invention is to provide a string of cable tools that do not require the use of heavy wrenches or circle jacks for making up the box or pin joints thereby saving considerable labor in the manipulation of the heavy wrenches.

Another object of my invention is to provide a device that permits changing the cable from one tool to another without the delay and labor involved in attaching the cable to the mandrel in the conventional manner, that of filling the tapered cavity with hot lead. The split bushing

2

employed in my device may be easily removed allowing the mandrel to pass through the jars for disconnecting one tool and to be inserted into another tool without delay, for in the use of drill tools it is necessary to change tools frequently thereby permitting one tool to be reconditioned while the other tool is in use.

A further object of my invention is to construct a device that provides sufficient circulation at the bottom of the drill hole to keep the heavy cutting in suspension.

A still further object of my invention is to provide a drill bit that is constructed in a manner that will cause rotation of a few degrees at a time at each downward blow, to prevent the chisel edge of the bit from striking repeated blows in the same place.

The object and purpose of my invention will become more apparent as the description proceeds when taken in conjunction with the drawings in which:

Figure 1 is a fragmentary cross-sectional view of the entire string of tools.

Figure 2 is a similar and large view of the upper portion of the tool enclosing the cable attached.

Figure 3 is an enlarged side view of the bottom portion of the tool including the drill head.

Figure 4 is a cross-section of the tubular body taken at the line 4—4 in Figure 3.

Figure 5 is a cross-section of the tubular body taken at the line 5—5 in Figure 3.

Figure 6 is a cross-sectional view taken at the line 6—6 in Figure 2.

Figure 7 is a cross-sectional view taken through the assembly at the line 7—7 in Figure 2.

Figure 8 is a cross-section taken at the line 8—8 in Figure 2.

Figure 9 is a top and side view of the valve.

Figure 10 is a top and side view of the ring forming a seat for the valve.

Figure 11 is a fragmentary view of the bottom jar collar and the top jar collar welded to the tubular jar body.

Figure 12 is a longitudinal cross-section of the mandrel bushing.

Figure 13 is a similar longitudinal cross-sectional view of the swivel mandrel.

Figure 14 is an outside side view of the drill head and

Figure 15 is a bottom view of the drill head.

Similar characters of reference indicate corresponding parts throughout the several views and referring now to the same, the character 20 shows a hollow main top tube connected to a hollow

main bottom tube 21, which is joined to the top tube 20 by means of a jar anvil 22 inserted within the tubes. This anvil 22 is provided with a longitudinal port 23. The outer peripheral surfaces of the tubes 20 and 21 at their juncture are provided with outwardly extending upper wings 24. Radially disposed upwardly from the wings 24 are a plurality of guide bars and a plurality of lugs for a drive clamp shown as 26. The inner enclosure formed by the main top tube 20 encases a jar body 27 having a top jar collar 28 welded to its upper end and a bottom jar collar 29 welded to its lower end. All of the parts, namely the body 27, the collars 28 and 29, being of cylindrical shape are hollow in their central portion. The upper end of the main tube 20 is provided with a hollow top collar shown as 30 which is provided with a seat 31 to accommodate a bevelled top 32 on the extreme upper end of the jar body 27. The bottom jar collar 29 has an enlarged portion 33 which accommodates a split hollow mandrel bushing 34, which in turn accommodates a hollow swivel mandrel 35 which is attached to the end of the cable shown as 36, and is provided with a tapered recess 37 to accommodate the flared out portion or open end of the cable 36 imbedded within lead or the like.

The hollow bottom jar collar 29 has countersunk apertures 38 and 38' disposed through the walls and the hollow mandrel bushing 34 has similar apertures 39 and 39' disposed through its walls and registering with the apertures 38 and 38'. These apertures 38 and 38', 39 and 39' accommodate a pin 40 extending therethrough retaining the swivel mandrel 35 within the mandrel bushing 34. Toward the lower end of the main top tube, there are shown two elongated apertures or openings 41. These apertures 41 extend upward so that their upper ends are above the level of the pin 40. This permits removing of the pin 40 and permits disengagement of the bushing 34 and the mandrel 35 when the string of tools are to be removed from the cable 36.

The main bottom tube 21 has torque vanes 42 of arcuated contour, extending outward from its outer peripheral surface, and also a plurality of long bottom wings 43 also radial in contour. The vanes 42 are disposed inside of the wings 43 and are bevelled toward their top and bottom ends to impart rotating motion to the tool as it rises and falls through the sludge in the drill hole. Near the upper end of the main bottom tube 21 are shown elongated slots 44 extending through its walls. Near the lower end of the slots 44 is shown an annular split valve seat 45 in the form of a ring attached to the inside surface of the tube 21 and acting as a seat for a valve assembly 46 having a bottom plate 47 and vertically extending members 48. This valve member 46 is free to move vertically upward and downward within the tube 21 between the valve seat 45 and the bottom of the jar anvil 22. At the extreme lower end of the hollow main bottom tube 21, is a cutter head 49 which has short bottom wings 50 extending upward therefrom to meet the end of the hollow tube 21. The cutter head 49 has a collar section 51 and is of circular contour. The bottom section 52 of the cutter head 49 is angularly disposed on its outer surface, having its lower edge wider than its upper end and an intermediate section 53 angularly disposed to accommodate the upper end of the section 52 and the lower end of the collar section 51. This intermediate section 53 is provided with openings through its walls and the inner walls of sections 52 and 53 are shown pro-

vided with a plurality of chisels or cutting members 55 extending vertically and having a flat front surface and a bevelled rear surface shown as 56. The extreme lower edge 57 of the bottom section 52 is tapered to a sharp point so that in the operation of the device the cutter head being provided with a continuous circular ring edge, which is above the level of the tapered ends of the chisels 55, surrounds the entire circumference of the cutter head, will cause the cutter head to chip a smooth round hole and due to the bevel 56, the chipped material will be forced into the path of the chisels 55. The pumping action of the valve 46 will keep the sludge in suspension during the up and down stroke and as all wings are in relatively the same arcuated contour, the cutter head down to the wings and the bevel 56 of the chisel 55 will always move the cutter head in the same counterclockwise rotating direction as indicated by the arrows in the drawings, and inasmuch as the mandrel 35 is free to move in the mandrel bushing 34, there will be no twisting strain on the cable 36 during the operation of the device.

Having thus described my invention, what I claim and desire to secure by Letters Patent in the United States is:

1. A device of the character described comprising in combination, a tubular main body, provided with a hollow cutter head at its lower end, a top collar inserted into its upper end and a hollow anvil inserted therein, a hollow jar body slideably disposed within said main body between said anvil and said top collar, said jar body being shorter than the distance between said anvil and top collar and employed to drive said cutter head, a cable disposed longitudinally within said top collar and jar body and extending outward therefrom for supporting and actuating said jar body, a mandrel attached to the lower end of said cable, a split mandrel bushing rotatably supported by the lower end of said jar body, said mandrel retained by said bushing, means for retaining said mandrel in rotatable engagement with the inside of said bushing, longitudinal slots through the walls of said main body, said slots of a diameter to permit removal of said mandrel and bushing, said cutter head having a sharp inwardly bevelled outer edge around its entire lower periphery, a plurality of chisel members extending inward from the walls of said hollow cutter head, said chisels having vertical front surfaces and bevelled rear surfaces and extending below the outer edge of said cutter head and radially formed wings extending outward from said tubular main body above said cutter head to aid in revolving said cutter head and body, said wings extending outward to a diameter less than the diameter of the cutter head.

2. A device of the character described comprising in combination, a tubular main body consisting of an upper and lower tube, a hollow cutter head disposed at the lower end of said lower tube, a top collar inserted into the upper end of said upper tube, a hollow jar anvil inserted into the body consisting of the upper and lower tube, a hollow jar body slideably disposed within said upper tube between said anvil and said top collar, said jar body being shorter than the distance between said anvil and top collar, a cable extending through said top collar and jar body for supporting and actuating said jar body, a mandrel attached to the lower end of said cable, a split mandrel bushing rotatably supported by the lower end of said jar body, said mandrel retained

within said bushing, means for retaining said mandrel in rotatable with the inside of said bushing, longitudinal slots through the walls of said upper tube, said slots of a diameter to permit removal of said mandrel and bushing, a slideably supported valve member disposed within said bottom tube below said anvil said valve caused to move up and down within said tube, elongated slots through the walls of said bottom tube adjacent to said valve said slots acting as exhaust ports for the material forced upward within said body, an annular valve seat arranged for supporting said valve member when in a down position, said seat attached to the inner walls of said lower tube, said cutter head having a sharp inwardly bevelled outer edge around its entire lower periphery, a plurality of chisel members extending inward from the walls of said hollow cutter head, said chisel members having vertical front surfaces and bevelled rear surfaces and extending below the outer edge of said cutter head, a plurality of radially formed wings extending longitudinally along portions of said top and bottom tubes, bevelled vanes disposed within the radius of said wings said wings and vanes aiding the revolving of said cutter head and body, said wings being of a diameter less than the diameter of said cutter head.

3. A device of the character described to be used in combination with a cable, said device comprising a tubular main body, a tubular jar anvil inserted into said main body, a jar body of tubular construction, said tubular main body having a tubular top collar inserted into its upper end, the bottom edge of said collar designed to contact the upper end of said jar body, a mandrel bushing, inserted into the lower end of said jar body, a swivel mandrel engaging said mandrel bushing, the end of said support cable attached to said swivel mandrel to allow rotation of said device, a pin extending through said mandrel bushing and jar body below the swivel mandrel within said bushing, a circular valve seat disposed within said main body at a point below said jar anvil, a valve member slideably mounted within the said main body, said main body provided with an elongated aperture through its walls in direct alignment with said valve to permit the exhausting of the material forced upward within said body, said main body provided with an elongated aperture through its walls, said aperture of a width to permit removal of said mandrel bushing when said mandrel is inserted therein. A plurality of longitudinal guide bars attached to the outer surface of said main body near the top thereof, a plurality of longitudinally disposed lugs attached to the outer surface of said body above said guide bars, radially formed upper wings longitudinally disposed and tapered at their upper and lower ends extending outward from said main body, longitudinal bottom wings of radial contour extending outward from the peripheral surface of said body near its lower end, a plurality of short tapered vanes projecting outward from the periphery of said body, within said upper and lower wings said wings and vanes disposed for assisting the revolving of said unit, a hollow cutter head, said cutter head wider at its lower cutting edge than the diameter of said wings, perforations in the tapered side walls of said cutter head, a plurality of chisels having tapered rear surfaces and vertical front surfaces, said chisels integrally constructed with the enclosure formed by said cutter head, the bottom edge of said cutter head being bevelled inwardly to provide an outer cutting edge around its entire peripheral surface, the bottom edge of said chisel extending below the cutting edge of said head, said chisel extending inward from the inner walls of said head to a distance to provide a hollow section between their inner edges in direct alignment with the tubular inside portion of said main top and bottom tubes.

5. A device of the character described to be used in combination with a support cable, said device consisting of a main top tube and a main bottom tube, said tubes forming a main body, a tubular jar anvil connecting said top and bottom tube and extending inward therefrom, a tubular jar body having an upper and lower collar, a tubular top collar inserted into the upper end of said main top tube, the bottom of said collar arranged for contact with the upper jar collar, a split mandrel bushing, said mandrel bushing inserted into the lower collar of said jar body, a swivel mandrel attached to the end of said support cable engaging said mandrel bushing, a pin extending through said bushing and lower collar on said jar body below said mandrel, a valve seat attached to the inner surface of said main bottom tube below the jar anvil joining said top and bottom main tube, a horizontal valve plate equipped with vertical guide members slideably mounted into the upper end of said bottom tube, said main bottom tube provided with elongated apertures through its walls in direct alignment with said valve, said apertures corresponding in length to the travel of said valve within said bottom tube, said main top tube provided with elongated apertures through its walls, said apertures of a width to permit removal of said mandrel bushing when said mandrel is inserted therein, a plurality of longitudinal guide bars attached to the outer surface of said top tube near the upper end thereof, a plurality of longitudinally disposed lugs attached to the outer surface of said top tube above said guide bars, a plurality of radially formed upper wings longitudinally disposed and tapered at their upper and lower ends extending outward from said main top and bottom tubes at their point of junction, long bottom wings of radial contour extending outward from the peripheral surface of said bottom tube near its lower end, a plurality of vanes bevelled toward the top and bottom projecting outward from the periphery of said bottom tube within said wings, a circular cutting head of hollow construction, said cutting head forming an integral part of said bottom tube, and wider at its lower cutting end than the diameter of said wings, perforations in the tapered side walls of said cutting head, a plurality of chisels having tapered rear surfaces and vertical front surfaces, said chisels integrally constructed with the enclosure formed by said cutter head, the bottom edge of said cutter head being bevelled inwardly to provide an outer cutting edge around its entire peripheral surface, the bottom edge of said chisel extending below the cutting edge of said head, said chisel extending inward from the inner walls of said head to a distance to provide a hollow section between their inner edges in direct alignment with the tubular inside portion of said main top and bottom tubes.

6. A cable drilling tool of the character described comprising, a tubular main body provided with a hollow drill head at its lower end, and a tubular auxiliary body having a tubular anvil disposed between them, a slidably mounted valve disposed within said main body below said anvil,

said valve supported at its lower end by a tubular seat extending inward from the walls of said main body, vertical elongated apertures extending through the wall of said main body along the path of said valve, said auxiliary body having a hollow collar permanently inserted within its upper end, and a tubular jar body slidably mounted between said hollow collar and anvil within said auxiliary body, the bottom of said jar body supporting a mandrel bushing, elongated slots within the wall of said auxiliary tubular body, said slots of a size to permit inserting the sections of said mandrel, a cable extending through the hollow collar at the upper end of said auxiliary tubular body and through the jar body, and a split mandrel attached to the lower end of said cable, said mandrel of a shape and contour to fit said mandrel body.

6. A cable drilling tool of the character described to be used in combination with a cable, said tool comprising, a main and an auxiliary tubular body attached to one another and having a tubular anvil disposed between them, said auxiliary body having a tubular collar inserted in its upper end, a tubular jar body slidably mounted within said auxiliary tubular body, said jar body of a length shorter than the distance between said tubular collar and tubular anvil, a cable extending through said collar and jar body, the lower end of said jar body adapted to receive the split hollow mandrel inserted therein, through slots within the walls of said auxiliary body to

permit inserting sections of said split mandrel, said mandrel of a shape and contour to fit the inside of said mandrel collar, said mandrel attached to the end of said cable, a valve seat extending inward from the wall of said main body below said anvil, a slidably supported valve inserted into said main body between said anvil and seat, elongated slots through the walls of said main body, said slots disposed between said anvil and valve seat, the main tubular body having a tubular cutting head attached at its lower end, said cutting head provided with cutting members having a vertical surface and bevelled surface extending upward from the lower end of said vertical surface, a plurality of vanes extending outside of said tubular bodies, said vanes being of a diameter equivalent to the diameter of said cutting head.
